SWING

Filed Oct. 21, 1929

Fig. 2.

INVENTOR
John C. De Bening
BY ATTORNEY

UNITED STATES PATENT OFFICE

JOHN C. DE PENNING, OF PORTLAND, OREGON

SWING

Application filed October 21, 1929. Serial No. 401,114.

The object of my invention is to provide a child's swing adapted to be operated by a combined arm and leg movement, so as to serve as an excellent piece of exercising apparatus and further to provide a swing of this character with the seat portion adapted to remain in a horizontal plane and the swing to move in a truly vertical plane. The latter objects permit my swing to be mounted indoors and close to walls or the like without incurring the possibility of injury to the child.

The details of construction and the mode of operation of my improved swing are hereinafter described with reference to the accompanying drawing, in which:

Fig. 1 is a side elevation thereof showing the manner of support;

Fig. 2 is a plan view thereof taken on the line 2—2 in Fig. 1; and

Fig. 3 is a vertical section taken on the line 3—3 in Fig. 2 thru the handle or operating portion of such swing.

My improved swing comprises a seat portion *a* preferably provided with upstanding sides *b*—*b'* and a back *c*, so that a child seated in such swing is supported and is prevented from slipping out of the seat. The forward end of the seat is formed into a tongue *a'*, which the child is adapted to straddle and the tongue at its forward end carries an operating handle *d* pivotally attached to the tongue *a'*. A bearing *e* is carried upon the undersurface of such tongue *a'* and a pivot pin *f* extends thru the operating handle and is journaled in such bearing *e*. The operating handle is composed of two spaced longitudinal members *g* connected together at the top by a handle *h* and at the bottom by a foot rest *i*. Both of such elements *h* and *i* are substantially longer than the width of the tongue *a'* and thus extend beyond the longitudinal members *g*.

The handle *h* has grips *h'* formed at the ends thereof of convenient size to be easily gripped by the hands of the child operator and the foot portion *i* is formed to retain the child's feet against slipping. Extending exteriorly of the members *g* are tie rods *j* consisting preferably of metal bolts, which rods

extend thru the handle and foot pieces *h* and *i* and securely tie such two members together, as well as press the longitudinal members *g* and prevent their bowing outwardly. Such tie rods *j* perform an additional function in 55 that they pass thru the ends of the pivot pin *f* and thus key such pivot pin against longitudinal displacement in the bearing *e*.

Such swing is preferably supported in the bights of supporting ropes *k* and *l*. Looped 60 ropes of this character are preferably provided, as it is more convenient to adjust the swing with respect to the horizontal plane when the ropes are fastened in this manner, although it is possible to provide four separate ropes in place of the two looped ropes, as is readily understood. The rope or ropes *k* extend thru holes arranged in the handle element *h* and thru aligned holes in the foot portion *i*, such holes being arranged a slight 65 distance outside of the tie rods *j* and the rope *l* extends thru the holes arranged in the portion *a2* of the seat which extends behind the back *c*.

The rope or ropes *k* and *l* are fastened to 70 a ceiling a substantial distance above the swing so that when such swing is operated the swing will traverse an arc of substantial length. The rope or ropes *k* support the forward end of the swing and the ropes *l* the 75 after end.

The swing is operated by a child sitting in the seat *a* with its back placed against the portion *c*, with its feet resting upon the foot portion *i* exteriorly of the members *j*, and gripping the handle *h* with its hands. By 80 rocking such member *d* about its pivot *f* backward and forward, motion will be given to the swing, the member *d* serving as a double-acting operating lever. The child in one direction pushes with its legs and pulls with its arms and in another direction reverses such operation and in this way uses all of the 85 body muscles. It is to be noted that the ropes *k* and *l* are of substantially the same length and thus when the seat portion *a* is adjusted to extend in a horizontal plane, such swing will continue to be maintained in such plane during the entire operation thereof, so 90 as to minimize the possibility of accident, 95 100

even when such swing is operated by a very young child.

The various portions of the rope *k* and *l* further are spaced apart the maximum distance, taking into consideration with the swing, so as to minimize the possibility of side sway. In other words, the elements of the supporting ropes *k* and *l* are spaced apart a substantial distance and of the same length and are thus adapted to travel along the same arcuate path, the spacing of the elements tending to maintain such path in a vertical plane.

I claim:

15 1. In a device of the character described adapted to be hung in a pendent swinging support, the latter comprising a pair of looped flexible elements spaced apart different distances, a seat portion carried in the bights of the more widely spaced of such looped elements, and a pivoted handle connected intermediate its ends to such seat portion and the other of such support elements extending longitudinally of such handle and connected thereto at a point spaced from the point of connection with such seat portion.

20 2. A swing of the character described comprising a seat having a forwardly extending tongue portion, a handle pivotally secured intermediate its ends to such tongue, said handle provided with transverse members arranged adjacent its ends, a support for such swing comprising two spaced flexible elements formed into pendent loops, one loop 25 being quite narrow and engaging the handle, passing thru alined eyes in the transverse members thereof, and the other thru spaced eyes at the rear edge of said seat.

25 3. A swing of the character described comprising a seat having a forwardly extending tongue portion, a handle pivotally secured intermediate its ends to such tongue, said handle provided with transverse members arranged adjacent its ends, a support for 40 such swing comprising two spaced flexible elements formed into pendent loops, one loop engaging the handle passing thru alined eyes in the transverse members thereof and the other thru spaced eyes at the rear edge of 45 said seat, the spacing of the eyes in the handle being substantially less than the spacing of those at the rearward edge of the seat, the latter being spaced apart a distance approximately the width of the seat.

50 55 4. A swing of the character described comprising a seat having a forwardly extending tongue portion, a handle pivotally secured intermediate its ends to such tongue, said handle provided with transverse members arranged adjacent its ends, a support for such 55 swing comprising two spaced flexible elements, one engaging the handle and the other passing thru spaced eyes at the rear edge of said seat and an upwardly inclined fixed back for such seat arranged adjacent the eyes

at the rear edge of the seat, thereby adapted to engage the rearward support to shorten the free swinging radius of the latter in one direction.

5. A swing of the character described comprising a seat having a forwardly extending tongue portion, a handle pivotally secured intermediate its ends to such tongue, said handle provided with transverse members arranged adjacent its ends, a support for such 75 swing comprising two spaced flexible elements, one engaging the handle and the other passing thru spaced eyes at the rear edge of said seat and a rearwardly and upwardly inclined fixed back for such seat arranged adjacent the eyes at the rear edge of the seat and overlying the latter, thereby adapted to engage the rearward support when at rest and to shorten the free swinging radius of the latter in one direction.

In testimony whereof he has affixed his signature.

JOHN C. DE PENNING.
